(57) **CLAIM**

The ornamental design for a veggie chopper, as shown and described.

DESCRIPTION

FIG. 1 is a front, right, and top perspective view of a veggie chopper, showing our design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a partial enlarged view of an area labeled 9 in FIG. 1 comprising a cutter.

The broken lines shown in the drawings are included for the purpose of illustrating portions of the veggie chopper that form no part of the claimed design.

1 Claim, 9 Drawing Sheets
